UNITED STATES PATENT OFFICE

132,151

DESIGN FOR A COMBINED DISPLAY RACK, OIL SAVER, AND WASTE CAN RECEPTACLE

Harvey J. Smith, Danville, Va., assignor to
W. Ira Barker, Danville, Va.

Application August 7, 1941, Serial No. 102,726

Term of patent 14 years

To all whom it may concern:

Be it known that I, Harvey J. Smith, a citizen of the United States, residing at Danville, Virginia, have invented a new, original, and ornamental Design for a Combined Display Rack, Oil Saver, and Waste Can Receptacle, of which the following is a specification, reference being had of the accompanying drawing, forming part thereof.

Fig. 1 is a perspective view of the article, showing my new design, viewed toward one end and one side.

Fig. 2 is an end elevation of the same, looking at the other end of the article.

Fig. 3 is a top plan view of the same.

Both sides of the article are alike, but the ends are different, as shown in Figs. 1 and 2.

What I claim is:

The ornamental design for a combined display rack, oil saver, and waste can receptacle, substantially as shown and described.

HARVEY J. SMITH.
